STATIONARY SUPPORT

James Edward Bailey and William Archibald
Albaugh, III, Richmond, Va.

Application November 26, 1940, Serial No. 367,162

2 Claims. (Cl. 211—11)

This invention relates to stationary supports and more particularly to supports adapted for use in connection with the drawers in filing cabinets.

One of the objects of this invention is the provision of a support adapted for disposition in a drawer of a filing cabinet.

Another object of this invention is the provision of a support consisting of a plurality of supporting members disposed in a drawer of a filing cabinet and adapted to retain filing folders in a substantially erect position.

Other objects and features will more fully appear from the following description and accompanying drawing, in which:

Fig. 1 is a sectional vertical side view of a filing cabinet drawer showing the support disposed therein; Fig. 2 is a sectional end view of the cabinet drawer showing the support therein, and Fig. 3 is a top plan view of said support.

Referring to the drawing, a drawer 1 adapted for disposition in the usual filing cabinet, not shown; but well known to the art, is provided with a channel 2, constituting part of a bottom 3 of said drawer.

A support 4 consists of a rectangular base 5 to which is attached a plurality of vertical stays 6 which are firmly held in spaced relation by said base and braces 7 respectively secured to each side of said stays.

It is obvious from the foregoing that when the support is disposed in the drawer the basal portion of said support is disposed in the channel and the stays project therefrom, in spaced rela-

tion, up into the drawer. The stays are adapted for keeping erect a plurality of filing folders 8. It is further obvious that the braces are housed within the channel and do not project beyond the bottom of said file drawer.

Without this stationary support the filing folders now lying in filing drawers tend to bend and assume positions that make it difficult for one to obtain such folders from the file and especially when the file is not filled with folders.

Having described this invention, what is claimed is:

1. In a device of the character described in combination with a drawer provided with a recess of a support disposed in said drawer consisting of a base provided with a plurality of stays secured to said base in spaced relation to each other and projecting upwardly into said drawer and having braces respectively secured to each side of said stays so that the latter may more firmly support a plurality of filing folders.

2. In a device of the character described in combination with a drawer having a recess of a support provided with a base adapted for disposition in said recess; a plurality of stays secured to said base in spaced relation to each other and projecting upwardly into said drawer and having braces respectively secured to each side of said stays; said braces adapted to be located in said recess.

JAMES EDWARD BAILEY.
